US00D818524S

(12) **United States Design Patent** (10) Patent No.: **US D818,524 S**
(45) Date of Patent: **** May 22, 2018**

(54) **INTELLIGENT PAYMENT TERMINAL**

(71) Applicant: **PAX COMPUTER TECHNOLOGY (SHENZHEN) CO., LTD.**, Shenzhen (CN)

(72) Inventors: **Deqiang Dong**, Shenzhen (CN); **Yuzhuo Wang**, Shenzhen (CN); **Dahai Chen**, Shenzhen (CN)

(73) Assignee: **PAX COMPUTER TECHNOLOGY (SHENZHEN) CO., LTD.**, Shenzhen (CN)

(**) Term: **15 Years**

(21) Appl. No.: **29/594,838**

(22) Filed: **Feb. 23, 2017**

(30) **Foreign Application Priority Data**

Dec. 30, 2016 (CN) 2016 3 0658706

(51) LOC (11) Cl. **18-01**

(57) **CLAIM**

The ornamental design for an intelligent payment terminal, as shown and described.

DESCRIPTION

FIG. 1 is a top perspective view of the intelligent payment terminal;

FIG. 2 is a bottom perspective view of the intelligent payment terminal;

FIG. 3 is a front view of the intelligent payment terminal;

FIG. 4 is a rear view of the intelligent payment terminal;

FIG. 5 is a left side view of the intelligent payment terminal;

FIG. 6 is a right side view of the intelligent payment terminal;

FIG. 7 is a top view of the intelligent payment terminal; and, FIG. 8 is a bottom view of the intelligent payment terminal. The broken lines shown in the drawings depict portions of the intelligent payment terminal that form no part of the claimed design.

1 Claim, 8 Drawing Sheets
